ELECTRON OPTICAL SYSTEM

Dennis Gabor, Rugby, England, assignor to General Electric Company, a corporation of New York

Application May 9, 1946, Serial No. 668,613
In Great Britain August 28, 1945

8 Claims. (Cl. 250—49.5)

1

My invention relates to electron optical systems and it has for its primary object to provide new and improved means and methods for correcting the spherical aberration encountered in electron lenses.

It is well known that the spherical aberration of electron lenses of the conventional type, whether electric or magnetic, is always of the same sign and, hence, cannot be corrected by any combination of such lenses. Accordingly, it is an object of my invention to provide a new type of lens which, alone or in combination with lenses of the conventional type, permits the correcting of the spherical aberration within a certain annular zone defined by the lens elements.

A lens constructed in accordance with my invention includes, along the axis thereof, a rotationally symmetrical conductor or core which is preferably a straight cylindrical wire, and coaxial with the core one or several rotationally symmetrical electrodes which are so arranged as to produce in the neighborhood of the core several fields which are of prevailingly radial direction. The core is supported by members which are not themselves rotationally symmetrical and which are arranged in such position as to be shielded from intense electric fields.

One of the features of my improved electron lens system is that electrons are permitted passage in an annular zone which extends to less than a full circle. Moreover, the fields in the system are so dimensioned that at least a part of the electron trajectories issuing from an axial or slightly extra-axial point are brought to a sharp focus.

The features of my invention which I believe to be novel are set forth with particularity in the appended claims. My invention itself, however, both as to its organization and method of operation, together with further objects and advantages thereof, may best be understood by reference to the following description taken in connection with the accompanying drawings in which Fig. 1 illustrates a phenomenon of spherical aberration as produced by electron lenses of the conventional type; Fig. 2 is a lens according to the invention with a single extra-axial electrode; Figs. 3 and 4 illustrate electron trajectories in the lens of Fig. 2 showing, respectively, the case of attractive and repulsive core potentials; Fig. 5 shows the combination of the lens of Fig. 2 with a magnetic lens of the conventional type and illustrates the zonal correction of spherical aberration; Fig. 6 is a modification illustrating the combination of two lenses embodying the inven-

2

tion; Fig. 7 is a graph showing the calculated focussing characteristic of the lens illustrated in Fig. 6 and its characteristic in combination with a magnetic lens of the conventional type; and

5 Fig. 8 is a cross-section of a lens according to the invention with two extra-axial electrodes in combination with a magnetic lens and illustrates certain constructional details of the system.

Theory and experiment have demonstrated, 10 that in all electron lenses of the conventional type the spherical aberration has the sign as illustrated in Fig. 1. An object point O is imaged by paraxial rays in an image point I₀. However, for rays which form initially larger angles α with 15 the axis the image point I_a shifts progressively nearer to the object point. In other words, the lens strength increases monotonously with increasing initial angle α . For small angles the law is approximately

$$20 \quad \frac{1}{f_a} = \frac{1}{f_0} (1 + C_\alpha^2) \quad (1)$$

where f_0 is the paraxial focal length, and f_a the focal length corresponding to the angle α . C is the coefficient of "first order" spherical aberration, which is always positive, and according to best theoretical evidence cannot be made smaller than about 0.2 with any lens combination of the conventional type.

25 Fig. 2 shows the simplest type of lens according to the invention. Conducting wire 1 is the core and is supported at both ends by thin radial wires 2 and 3 of sufficient stiffness to keep it stretched. At one or both ends the core may be fitted with spherical ends 4 and 5 which, apart from facilitating a neat connection with the supporting wires serve as parts of the limiting aperture. The supporting wires are clamped in rods 6 and 7, of which one is shown elastically supported by a spring 8. These in turn are fixed to the shields or outer electrodes 9 and 10 with apertures sufficiently small to define the limits of the electric field and insure that no appreciable electric fields will penetrate to the neighborhoods of the supports 2 and 3, so that the fields in the lens can be considered as rotationally symmetrical. In operation shields 9 and 10 are connected, whereas before operation they may be connected temporarily to some low voltage source, 30 in order to heat the wire and clean its surface from contaminations and absorbed gases. In operation the annular electrode 11 is maintained at a potential positive or negative relative to the core, as will be explained in connection with the following figures.

Fig. 3 illustrates electron trajectories if the annular electrode is negative with relation to the core, that is to say, if the core has a positive charge which attracts the electrons. It can be seen that by itself this system has no focussing effect. The deflection of the electrons decreases very rapidly with increasing initial angle, that is, an effect of opposite sign to that illustrated in Fig. 1. Similarly, if the core has a repellent, negative charge, as illustrated in Fig. 4, the trajectories will not come to a real or virtual focus, but will suffer deflections rapidly decreasing with increasing initial angle.

In order to understand these effects quantitatively, it is sufficient to assume, as a first approximation, that the charge Q on the core wire is concentrated in a point of the axis. The dynamical problem is thus reduced to Newton's problem of two bodies, attracting or repelling one another with an inverse square law. If an electron with charge $-e$ and energy eV (V being the "volt energy") is shot towards the charge Q in such a way that in the absence of attraction or repulsion it would pass it at a distance p , and if V is large enough, the trajectory will be a hyperbola. The angle θ between the asymptotes gives the total deflection which the electron has suffered in the field of Q . This is given by the equation

$$\tan \frac{1}{2}\theta = \frac{Q}{pV} \quad (2)$$

As only small deflections will be considered, $\tan \frac{1}{2}\theta$ is very nearly $\frac{1}{2}\theta$. The charge Q can be expressed $Q = cE$, where c is the mutual capacity of the core and the extra-axial electrode, and E is the voltage applied between them. As the deflections are small, p can be replaced by the distance r of the trajectory from the axis where it passes nearest to O. Thus we obtain the useful approximative formula

$$\theta = 2 \frac{cE}{rV} \quad (3)$$

In this formula both c and r are to be measured in centimeters, E and V in volts. The formula shows clearly that a system according to the invention as illustrated in Figs. 2-4 is not by itself a lens in the usual sense of the word, as a lens proper must have a deflecting effect proportional to r , not to $1/r$. Hence these systems are to be used not by themselves, but as components of combinations, to be described later.

In order to estimate the deflecting power, the capacity c may be substituted from the approximative formula

$$c = 2L/\log(b/a) \quad (4)$$

where L is the axial length of the annular electrode 14, b its inner diameter, and a is the diameter of the core. This equation is exact only in the case of long, cylindrical systems, but permits us to estimate the order of the effect. As an example let $L = 0.2$ centimeter, $b = 0.2$ centimeter, and $c = 0.01$ centimeter. This gives $c = 0.068$ centimeter. Let the applied voltage be $E = 500$ volts and assume electrons of 50 kilovolts energy, i. e., 50,000 volts. If these electrons pass through the electrode system at a distance of 0.05 centimeter from the axis the deflection is

$$\theta = 2 \frac{0.068}{0.05} \frac{500}{5 \times 10^4} = 0.0272 \text{ radians} = 1^\circ 34'$$

which can be positive or negative, according to the sign of E . This is a deflection comparable with those obtained in lenses of the conven-

tional type. It corresponds to a focal length of $0.05/0.0272 = 1.34$ centimeters for electrons traversing the lens at an axial distance of 0.05 centimeter. The limiting feature for the strength of these new systems is the electric gradient at the surface of the core, which is approximately $2E \log(b/a)/a$, and in the above case 30,000 volts per centimeter. In the case of a negative core this is not far from the limit at which autoelectronic discharge sets in. With a positive core considerably higher gradients are permissible. The danger of autoelectronic discharge can be reduced by using wires of clean, smooth metallic surface, which are cleaned and freed from absorbed gases by flashing before operation.

Fig. 5 is a combination of a simple system as described in connection with Figs. 2 and 3 with a magnetic lens 12 of the conventional type. The core 1 is assumed to carry a positive, attractive charge. Electron trajectories which are permitted to pass the system are shown in continuous lines, trajectories which are cut out by the aperture in interrupted lines. The spherical aberration of the magnetic lens is overcorrected for those trajectories which pass too near to the core, and under-corrected for those which pass at a too large distance from it. It is compensated in a certain narrow annular zone which alone is admitted for imaging, and these trajectories image the point O in the point I.

A focussing effect according to the invention is produced also by a combination of two systems, one with attracting, the other with repellent core charge, as shown in Fig. 6. The first annular electrode 14 has a negative, the second, 13, a positive potential relative to the core. Trajectories which pass nearer to the core suffer stronger positive deflections in the first, and stronger negative deflections in the second part of the system than trajectories at a larger distance from the axis, and as a result they are united in the same axial image point.

Fig. 7 is a quantitative illustration of this effect. In this graph the abscissae are the sines of the angles α , only little different from the angles themselves, measured in radians. The ordinates correspond to the "power" or "strength" s of the lens, which is defined by

$$s = \frac{1}{x_0} + \frac{1}{x_1} \quad (5)$$

where x_0 is the distance of the object point O, to the left of the lens, measured from the center of the second part of the system 13, x_1 is the distance of the image point, considered as positive when it is at the right. It can be seen that this definition is formally the same as for the "power" of an ordinary lens, but with the difference that s depends on the angle α . In the graph of Fig. 7, not s is plotted, but the dimensionless product

$$sx_0 = 1 + \frac{x_0}{x_1} \quad (6)$$

which is a convenient relative measure. It assumes the value unity when $x_1 = \infty$, that is to say, if O is the focal point for a ray with a certain angle α , and it is zero if $x_1 = x_0$, i. e. if the total deflection is zero. In all systems according to the invention the value zero is approached for large values of α , so long as the conventional lens effect is neglected for the sake of simplicity.

The curve labelled 14+13 shows the calculated values of sx_0 for a combination as illustrated in Fig. 6. For simplicity the distance of the center 75 of 14 from O may be assumed as 1 centimeter,

though it is evident that the curve remains unchanged if all dimensions are increased or reduced in the same proportion. The distance between the centers of 11 and 13 is 0.5 centimeter. The constant cE/V , which occurs in Equation 3 is assumed as +.0015 centimeter for the first part of the system, and -.00125 centimeter for the second. That is to say, that the repulsive part of the lens has $\frac{1}{2}$ of the power of the attractive part. It can be seen from Fig. 7 that for $\alpha < 0.075$ the lens is dispersive, but for larger angles α it has a slight positive power, which reaches a maximum of 0.0165 at $\alpha = 0.105$. This in itself is not sufficient to produce a real image of O, in fact the image is virtual and only 0.0165 centimeter behind O the object point. But the lens with the data as described is suitable for correcting the spherical aberration of a strong magnetic lens. This is illustrated by the curves 12 and 11+13+12. The first of these shows the spherical aberration of a magnetic lens, according to Equation 1, with $f_0 = 1$ centimeter and $C = 0.4$. As a first approximation, the errors of the combination can be obtained by addition. This is carried out in the curve 11+13+12. It can be seen that the power of the combination is almost constant between about $\alpha = 0.12$ and $\alpha = 0.17$. In practice the best compensation can be found experimentally, by adjusting the voltages S of the annular electrodes.

Even better combinations than the one here described can be obtained by three annular electrodes, of which the two outer ones have negative potentials, while the middle electrode is positive.

A particularly important application of the invention is the correction of the objectives of electron microscopes. Fig. 8 is a section of the magnetic objective of a microscope, embodying a two-electrode system according to the invention. The whole system is shaped as a cone, which fits accurately into a conical bore machined into the pole pieces 14 and 15, separated by the non-magnetic distance piece 16, so that it can be easily removed and replaced. The object carrier 17 fits into a cartridge 18. The cartridge 18 carries at its lower end the supporting wire 2, which assures elastic tension of the core 1. The lower end of core 1 is fixed in a rod 19 which is made of a ductile metal, such as soft copper, so that it can be used for centering core 1. The electrodes 11 and 13 are machined in top-hat shape, and are accurately distanced by means of insulators 20. The whole system, including the pole-piece inserts 21 and 22 is screwed together by means of screws 23. The screw holes are on as large a diameter as possible, and polygonally distributed, in order to disturb the rotational symmetry of the magnetic field as little as possible. The potentials of the annular electrodes are applied through leads 24 of which I have shown only the lead connected to electrode 11.

In operating this objective it is not necessary, nor practical, to flood the whole annular aperture with electrons. The theory of the diffraction of a microscope with an annular aperture shows that little is gained by opening up the annular aperture beyond a sector about as wide in tangential direction as the difference of the radii. This limitation need not be effected by material apertures, but can be obtained by directing an illuminating beam of suitable restricted divergence on a part of the aperture. It may be noted that the magnetic lens twists the electron trajectories around the axis, hence it can happen that the supporting wires at both ends of the core must be arranged in

different meridian planes, not in the same plane, as shown in this, and all the previous figures.

Only the principle and a few embodiments of the invention have been described in this application. Other modifications and applications will be obvious to those skilled in the art. I, therefore, desire in the appended claims to cover all such modifications as fall within the true spirit and scope of the foregoing disclosure.

What I claim as new and desire to secure by Letters Patent of the United States is:

1. An electron lens comprising a disk-like electrode having a central aperture therein along which an electron beam is adapted to be projected, and a conductive member transverse to said electrode and extending substantially axially of said aperture, said conductive member being maintained at a potential difference with respect to said electrode to correct the spherical aberration of said beam caused by said electrode.

2. An electron lens comprising a rotationally symmetrical conductor, a rotationally symmetrical electrode coaxially aligned therewith, said electrode having a central aperture through which said conductor projects, said electrode being arranged to produce a radially directed electric field, and said conductor being maintained at a potential difference with respect to said electrode.

3. An electron lens comprising a rotationally symmetrical conductor, a rotationally symmetrical electrode coaxially aligned therewith, said electrode having a central aperture through which said conductor projects, said electrode being arranged to produce a radially directed electric field, and means for defining said field and supporting said conductor, said conductor being maintained at a potential difference with respect to said electrode.

4. An electron lens comprising a disk-like electrode having a central aperture therein along which an electron beam is adapted to be projected, a conductive member arranged substantially transverse to said electrode and extending substantially axially of said aperture, said conductive member being maintained at a potential difference with respect to said electrode, and means surrounding said member and said electrode for exerting a deflecting force on said beam, the magnitude of said force and the potentials of said member and said electrode being adjusted to permit passage of said beam through said aperture substantially without any spherical aberration thereof.

5. An electron lens comprising a pair of disk-like electrodes having axially aligned central apertures therein through which an electron beam is adapted to be projected, and a conductive member arranged transverse to said electrodes and extending substantially axially of said apertures, said electrodes being maintained at different potentials with respect to each other and with respect to said member to compensate the spherical aberration of said beam during passage through said apertures.

6. An electron lens system comprising a pair of rotationally symmetrical electrodes having axially aligned apertures, a rotationally symmetrical conductor supported along the axis of said electrodes, said electrodes being maintained at potential differences with respect to each other and with respect to said conductor, and magnetic means surrounding said electrodes and said conductor to deflect an electron beam projected axially of said apertures.

7. In an electron optical system of the type

which employs a narrow beam of electrons, means for deflecting said beam, said means being subject to spherical aberration of a predetermined characteristic, and means to compensate said aberration comprising means for causing spherical aberration of said beam of opposite characteristics and of substantially equal magnitude as said predetermined characteristics.

8. In an electron lens system, means for compensating spherical aberrations of said system comprising three rotationally symmetrical and substantially parallel electrodes having coaxially aligned apertures, a rotationally symmetrical conductor arranged along the axis of said electrodes, the outer of said electrodes being maintained at a negative potential with respect to said conduc-

tor and the central of said electrodes being maintained at a positive potential with respect to said conductor.

DENNIS GABOR.
